UNITED STATES PATENT OFFICE.

FRED LOBNITZ, OF CROOKSTON, SCOTLAND.

ROCK-CUTTING APPARATUS.

1,149,846.

Specification of Letters Patent. Patented Aug. 10, 1915.

Application filed September 5, 1914. Serial No. 860,351.

To all whom it may concern:

Be it known that I, FRED LOBNITZ, a subject of the King of Great Britain, residing at Crookston, Renfrewshire, Scotland, have invented certain new and useful Improvements in Rock-Cutting Apparatus, of which the following is a specification:

This invention relates to what is known as rock-cutting apparatus, that is, apparatus for breaking up or cutting rocks, boulders, stones, or hardened earth, or combinations of earth and stone, either under water or on dry land. Such apparatus is usually employed in conjunction with, or as an auxiliary to, a dredging plant when forming or deepening rivers, canals, channels, harbors, and other water ways, and also for breaking up or disintegrating the ground when making excavations on dry land for railway foundations and other formations and structures. In apparatus of this kind it is usual to employ one or more rock cutters, which may weigh from 5 to 25 tons or so and it has been the general practice, heretofore, to suspend the heavy cutter by means of a single wire rope which passes over a pulley on a sheer legs structure and is secured to the barrel of a hoisting winch which latter is operated by power. In the past, considerable trouble and expense has been occasioned through the heavy cutter, when suspended by the rope, spinning around to a greater or less extent and, in so doing, opening out and fraying the strands of the wire rope with the result that it soon breaks and requires to be repaired or renewed. To resist the spinning action as much as possible so called "non-spinning" ropes or other arrangements have been employed but such arrangements, while being costly, only partially meet the difficulty. For many years I have carried out experiments with the view of providing a form of suspension which will prevent the opening out and fraying of the wire ropes, thereby obviating the employment of expensive "non-spinning" ropes and, at last, I have invented an arrangement which is not only simple but is very effective and which enables wire ropes of sufficient strength to be used without danger of the same being rapidly destroyed as heretofore. By means of this invention the cost of cutting or breaking up rocks will be very materially reduced.

The invention consists in suspending the

cutter by means of a single wire rope of the required strength and this rope is arranged in such a way that it forms a double and balanced suspension for the rock cutter. With this double suspension I find that the strands of the rope, even although it is not a non-spinning rope, are not opened out and frayed by the movements of the cutter as heretofore, while the spinning motion of the cutter is also checked more or less.

In order that the invention may be clearly understood I have hereunto appended explanatory drawings whereon I have shown, simply by way of illustration or example, one convenient mode of carrying out the invention in connection with a rock cutting vessel such as used when deepening canals and harbors.

Figure 1 is a side elevation of the rock-cutter vessel and showing the cutter suspended from the wire rope. Fig. 2 is an end elevation showing the double suspension of the cutter. Fig. 3 is an enlarged sectional view of the barrel of the hoisting winch. Fig. 4 is an end elevation of the same. Figs. 5 and 6 are respectively vertical and cross sectional views showing the method of attaching the ends of the wire rope to the cutter.

On the drawings the same reference letters and numerals wherever repeated indicate the same parts:

a is the rock cutting vessel, *b* the hoisting winch thereof, *c* the structure on the vessel for carrying the rock cutter, *d* the double pulley over which the wire rope runs, and *e* the cutter.

In carrying out the invention according to the arrangement shown on the drawings, the wire rope 1 is passed over a bollard portion 3 formed on one end of the barrel 5 of the hoisting winch *b* and then its one end 1^a is led around a half bollard portion 2 and its other end 1^b is led around a second half bollard portion 4, these portions being also formed on the barrel, and then both ends 1^a, 1^b, are wound side by side around the barrel (see Fig. 3) lying in grooves 6 thereon and, thereafter, the ends are led up and over the pulley *d* on the usual sheer legs structure and down, side by side, to the cutter to which the ends are secured by passing them into a circular opening 7 in the cutter and then clamping them in position by means of clamps 8, 9, tightened up by

screws 10. The clamps 8, 9, have double grooves 11 suitable for engaging the two rope ends 1^a, 1^b.

On the drawings, Figs. 3 and 4, the rope ends 1^a and 1^b are distinguished by having the strands indicated in the one case with full lines and in the other with dotted lines.

By passing the rope around the bollard portions 2, 3, 4, a balanced attachment is provided, the rope, when the weight of the cutter comes upon it, at first, slipping over the bollard portions to an extent sufficient to make the stress equal on both portions of the rope, and sufficient frictional grip is thereafter given to insure proper action of the rope and winch barrel in the hoisting operation. Further, the necessity for a spliced connection is avoided.

With this arrangement, by operating the winch, the cutter can be raised and lowered in the usual way and as the rope ends are connected, side by side, and at a short distance from one another they tend to lessen or prevent the spinning around of the cutter. Any spinning that does take place merely tends to twist the rope ends (above the connection with the cutter) about one another.

Having now fully described my invention what I claim and desire to secure by Letters Patent is:—

1. In rock cutting apparatus the combination with a rock cutter and a winch with winch barrel for raising and lowering same, of a double rope suspension consisting of a single rope which passes around bollard portions on the winch barrel and has its ends secured side by side to the top of the rock cutter.

2. In rock cutting apparatus the combination with a rock cutter and a winch with winch barrel for raising and lowering same, of a double rope suspension consisting of a single rope which passes around bollard portions, one of circular formation and the other two of semi-circular formation, on the winch barrel and has its ends secured side by side to the top of the rock cutter.

3. In rock cutting apparatus the combination with a rock cutter and a winch with winch barrel for raising and lowering same, of a double rope suspension consisting of a single rope which passes around the winch barrel and has its ends secured side by side to the top of the rock cutter, the ends being inserted in an opening in the cutter and secured by clamping means.

4. In rock cutting apparatus having a heavy cutter operated by means of a winch with winch barrel, and a double rope sus-

pension for the cutter consisting of a single rope having its ends secured side by side to the top of the cutter and also passed over bollard portions on the winch barrel.

5. In rock cutting apparatus, a heavy cutter operated by means of a winch with winch barrel, and a double rope suspension for the cutter consisting of a single rope having its ends secured side by side to the top of the cutter and passed over bollard portions on the winch barrel so as to give a balanced suspension.

6. In rock cutting apparatus, a heavy cutter operated by means of a winch with winch barrel, and a double rope suspension for the cutter consisting of a single rope having its ends secured side by side to the top of the cutter and passed around a central bollard portion on the winch barrel and two diametrically opposite bollard portions on said barrel.

7. In rock cutting apparatus, a heavy cutter operated by means of a winch with winch barrel, and a double rope suspension for the cutter consisting of a single rope having its ends secured side by side to the top of the cutter and passed over three bollard portions on the winch barrel.

8. In rock cutting apparatus, a heavy cutter operated by means of a winch with winch barrel, and a double rope suspension for the cutter consisting of a single rope having its ends secured side by side to the top of the cutter and passed around a central bollard portion on the winch barrel and two semi-circular bollard portions on said barrel.

9. In rock cutting apparatus the combination with a rock cutter and a winch with winch barrel for raising and lowering same, of a double rope suspension consisting of a single rope passed around bollard portions on the winch barrel and having its ends both connected to the rock cutter.

10. A rock cutting apparatus having, in combination, a rock cutter, a rope suspension therefor and winding means for raising the cutter and allowing it to drop, the said suspension being double the two ends of the rope suspension, being secured by means of a double clamp in the end of the rock cutter and being also secured by a balancing arrangement to the winding means.

In testimony whereof I affix my signature in presence of two witnesses:

FRED LOBNITZ.
